(57) **CLAIM**

The ornamental design of a webbing bag strap, as shown and described.

DESCRIPTION

FIG. 1 is a perspective view showing the right side, rear side, and front side of an embodiment of an ornamental design for a webbing bag strap.

FIG. 2 is a front view of the straightened webbing bag strap. FIG. 3 is a rear view of the straightened webbing bag strap. FIG. 4 is an abbreviated straightened left side view of the webbing bag strap.

FIG. 5 is a perspective view showing the left side, rear side, and front side of an embodiment of the webbing bag strap when it is tied in a loop.

FIG. 6 is a top view of the webbing bag strap; and, FIG. 7 is a bottom view of the webbing bag strap.
